UNITED STATES PATENT OFFICE

LOUIS F. BLUME, OF PITTSFIELD, MASSACHUSETTS, ASSIGNOR TO GENERAL ELECTRIC COMPANY, A CORPORATION OF NEW YORK

RATIO-ADJUSTING SWITCH

Application filed October 3, 1929. Serial No. 397,124.

My invention relates to switches. The general object of the invention is to provide a switch having main current carrying contacts with an improved arrangement of automatically controlled arcing contacts to prevent injury to the main contacts when the switch is operated to open or close a circuit or to change circuit connections while the circuit is carrying current. The invention may be applied with advantage and will be explained in connection with a switch of the type disclosed in Figures 5 and 6 of my United States Patent No. 1,535,807, issued April 28, 1925.

Other objects and advantages will be apparent from the following description taken in connection with the accompanying drawings in which Fig. 1 shows a switch, partly in section, made in accordance with the invention, and Figs. 2, 3 and 4 are sectional views on the lines 2-2, 3-3 and 4-4 respectively of Fig. 1.

Like reference characters indicate similar parts in the different figures of the drawings.

The particular switch shown in the drawings includes a plurality of spaced conducting rods or terminals 10, 11, 12, 13, 14 and 15 supported between a pair of insulating plates 16 and 17 and surrounding a central shaft 18 carried in bearings in the plates 16 and 17. In Fig. 1, the terminal 15 is removed and other parts are shown in section to reveal the structure more clearly. Six of the terminals are shown spaced uniformly about the shaft 18 although it will be apparent that a larger or smaller number may be used if desired. The desired connections between the terminals are made by a connector 19 rotatably supported about an offset portion of the shaft 18 and including movable contacts 20 and 21 which are secured to the body of the connector 19 by springs 22.

The connector 19 is provided with a rigid arm 23 with an anti-friction roller 24 at its outer end. The arm 23 is at the end of the connector 19 nearest the plate 16 which has a recess 25 into which the roller projects. Grooves 26 extending radially from the recess 25 cooperate with the shaft 18 to shift the connector 19 and its contacts 20 and 21 between their different terminal connecting positions.

With the parts in the positions shown in the drawings, the terminals 10 and 11 are connected together by the connector. To shift the connector to the position in which connection is made between the terminals 10 and 15, the shaft 18 is rotated in a clockwise direction as seen in Fig. 2, the offset portion of the shaft which carries the connector moving in a circular path about the axis of rotation of the shaft. During the first part of this rotation of the shaft 18, the contacts 20 and 21 are in engagement with and are held between the terminals 10 and 11 so that the connector is forced to rotate in a counter-clockwise direction, the roller 24 approaching the radial groove nearest the terminal 13. Further clockwise rotation of the shaft 18 moves the roller 24 into this radial groove and withdraws the contacts 20 and 21 from the terminals 10 and 11. The engagement of the roller 24 in the radial groove now forces the connector to continue to rotate in a counter-clockwise direction and the contacts 20 and 21 to approach the space between the terminals 10 and 15. Finally, the contacts 20 and 21 are moved into this space and forced by a toggle action firmly into contact with the terminals 10 and 15, the roller 24 being withdrawn from the radial groove and moved into a position midway between the grooves nearest the terminals 12 and 13. This operation may be repeated to shift the connector to other positions connecting any two adjacent terminals. It is obvious that by rotating the shaft 18 in the opposite or counter-clockwise direction, the connector will be shifted in a clockwise direction opposite to that just described; for instance, from the terminals 10 and 11 to the terminals 11 and 12.

The terminals 10 to 15 and contacts 20 and 21 are adapted to carry current continuously without injury but these contacts cannot be used to make or break the current without injury to both the contacts and terminals by arcing at the surfaces where the current is made or broken. To avoid this injury to the main contacts and terminals, an improved arrangement including auxiliary arcing contacts is provided. Any injury due to arcing takes place at these auxiliary contacts which

are simple and inexpensive and which may be easily replaced whenever desirable.

An auxiliary connector, including the arc-ing contacts 27 connected together by a spring member 28, is secured to the outer end of an arm 29 projecting from a sleeve 30 surround-ing the shaft 18. The sleeve 30 with its arm 29 and the auxiliary connector are arranged to rotate freely about one end of the shaft 18 beyond its offset portion so that the connector rotates in a circular path about the axis of rotation of the shaft 18. The main connector 19 carries a pin 31 which projects into a groove 32 in a plate 33 secured to the arm 29. When-ever the main connector 19 moves to shift its main contacts 20 and 21 from one contact making position to another, the pin 31 will engage one side or the other of the groove 32 and shift the arm 29 with the auxiliary arc-ing contacts 27 between the same contact making positions. Each of the terminals 10 to 15 is tubular and has its inner side cut away opposite the arc-ing contacts 27. A small cylindrical fixed arc-ing contact 34 is secured within each of the tubular terminals 10 to 15 at its cut-away portion and the spring member 28 forces the movable arc-ing contacts 27 against these fixed contacts 34 as shown in Figs. 3 and 4. The pin 31 controls the auxili-ary connector so that the auxiliary contacts and the spring member 28 always connect the same two terminals that are connected together by the main connector.

The main contacts 20 and 21 move from one contact making position to the next through a curved path which is convex toward the shaft 18 as already explained and the motion of the contacts at each end of this path has a large radial component toward or away from the shaft. The outer end of the groove 32 in the plate 33 is also enlarged so that there is some free space in this groove at each side of the pin 31. The main contacts 20 and 21 therefore leave the two main terminals with which they have been in contact before the pin 31 engages one side or the other of the groove 32 and therefore before the auxiliary arc-ing contacts start to move, the latter then carrying all the current and preventing any arc-ing at the main contacts as these are opened. The pin 31 is then drawn back into the narrower part of the groove 32 and engages one of its sides to shift the arc-ing contacts to the next contact making position. It will be apparent that the arc-ing contacts will reach this next contact making position while the pin 31 is still in the narrower part of the groove 32 and that the main contacts will finally be forced radially outward into the new position. In changing from one contact making position to the next, therefore, the circuit is always broken last and made first through the arc-ing contacts and no arc-ing can occur at the main contacts.

What I claim as new and desire to secure by Letters Patent of the United States, is:

1. A switch including a plurality of terminals, a main terminal connector, an auxiliary terminal connector, means for moving said main connector from one terminal connecting position to another, and means for moving said auxiliary connector between the same terminal connecting positions during the motion of the main connector, whereby the main connector is protected from arc-ing. 70 75

2. A switch including a plurality of terminals, a main terminal connector, an auxiliary terminal connector, means for moving said main connector from one terminal connecting position to another, and means controlled by said main connector moving means for moving said auxiliary connector between the same terminal connecting positions during the motion of the main connector, whereby the main connector is protected from arc-ing. 80 85

3. A switch including a shaft having an offset portion, a plurality of terminals spaced about said shaft, a main connector rotatable on the offset portion of the shaft, means for guiding the main connector from one terminal connecting position to another as the shaft is rotated, an auxiliary connector rotatable on said shaft, and a pin and groove connection between said connectors. 90 95

4. A switch including a shaft having an offset portion, a plurality of terminals spaced about said shaft, a main connector rotatable on the offset portion of the shaft, means for guiding the main connector from one terminal connecting position to another as the shaft is rotated, an auxiliary connector rotatable on said shaft, and a pin and groove connection between said connectors, a portion of said groove being enlarged to provide lost motion between said connectors during part of their motion between terminal connecting positions. 100 105 110

In witness whereof, I have hereunto set my hand this 30th day of Sept., 1929.

LOUIS F. BLUME.
